US0D1048999S

(12) **United States Design Patent** (10) **Patent No.:** **US D1,048,999 S**
(45) **Date of Patent:** **** Oct. 29, 2024**

(54) **CAR COVER**

(71) Applicant: **Xiaofei Lu**, Zhumadian (CN)

(72) Inventor: **Xiaofei Lu**, Zhumadian (CN)

(**) Term: **15 Years**

(21) Appl. No.: **29/953,102**

(22) Filed: **Jul. 19, 2024**

(51) LOC (14) Cl. **12-16**

(52) U.S. Cl.

USPC **D12/401**

(58) **Field of Classification Search**
